DUAL PROPELLER

Thomas R. Tarn, Pittsburgh, Pa.

Application October 17, 1940, Serial No. 361,485

3 Claims. (Cl. 170—165)

This invention relates to new and improved fluid actuating propeller arrangements. And, more particularly, it pertains to the handling and steering of vessels such as tow-boats or craft that are provided with actuating propellers of the screw type.

The successful navigation of inland streams and rivers requires the incorporation of features in power craft builded for such purpose that will enable the operators to handle the craft in spite of restricted depth of the streams, tortuous channels, bends and turns, variations in the swiftness of flow, traffic conditions, seasonal variations, and other contingencies that complicate the problem of building power craft for safe and expeditious movement of tows or of a fleet of tows or barges. That is, it is customary for a towboat to propel a group of tows or barges from port to port. For many years the so-called paddle wheel or stern wheel type of river boat has been used on the western rivers of this country. Later, the so-called screw type of propeller boat was introduced from foreign sources, being designed primarily as a packet or free running boat and not for towing barges "on the head" in the time-proven and economical manner employed on the Ohio and Mississippi River system.

In its original conception, the imported craft was an utter failure as compared with the stern-wheel boat in its ability to maneuver large tows of heavily laden barges. I was able to make certain constructional changes in the hull design and arrangement of the underwater appurtenances in a screw-type of river boat or craft that would effectively increase its propelling and handling ability, particularly from the standpoint of the operation of the rudders. As shown in my Patent 1,327,643, a twin-screw tunnel type of boat provided with propellers adjacent opposite sides thereof and with suitable governing rudders, could be greatly increased in maneuverability by controlling the rudders on one side independently of those on the other side. In a later Patent 1,346,279, I showed a chambered type of screw propeller tow-boat arrangement which also met with considerable favor.

Although I have been able to increase the effectiveness of the steering, flanking, and twisting operations in a boat of this type, whereby its operative results compare favorably with the performance of the stern-wheel boat, it still has limitations as to its operation. This can be appreciated from a study of the chart of Figure

4 of the drawings wherein the full line curve A shows the thrust per shaft horse power of a screw propeller for a scaled speed range where a conventional single propeller is propelling ahead. The dotted curve C shows the relationship where the same propeller was reversed to move the boat astern. The drop-off in horse power and thrust is substantial and is particularly great from a percentage standpoint due to uncontrollable structural factors. It is thus apparent that for the present state of the art, the loss of effective thrust entails a material loss of efficiency. This is an important loss where a boat is to be used for the above-mentioned purposes and must be maneuvered within limited space requirements as when entering or leaving a lock chamber or navigating between bridge piers or other structures of an engineering character.

15 Constructional and other difficulties give rise to an inherent inability of the conventional screw propeller type of boat to propel astern with the same facility as it propels ahead. In a boat of this type, it is customary to employ a so-called flanking rudder or rudders ahead of the propeller wheel and a so-called steering rudder or rudders behind or astern of the propeller wheel. Space limitations prevent the installation of flanking rudders of the same large area as the steering rudders. And, the position of the flanking rudder in the propeller wake of least velocity where the propeller is rotated for a backing-flanking operation constitutes another important factor from the standpoint of maneuvering the tow. An increased effectiveness in backing would automatically increase the effectiveness of flanking, and if this is obtained, the twin-screw type of tunnel boat will be established as the equal or superior in all respects to the stern-wheel type of boat as an outstanding power medium to meet the demands for safe and expeditious movement and control of large tonnage when assembled or grouped in the accepted western river fashion.

20 40 Ordinarily boats move forwardly a greater part of the time; consequently in designing propellers it is usual to provide propelling surfaces that favor forward propulsion. Those skilled in the art know that blades of the propellers should have certain shape characteristics for maximum efficiency and effectiveness of propulsion. When these characteristics are incorporated in the ahead propulsion surfaces the needed metal structure for providing strength to the blades constitutes a factor precluding and

45 50

not conducive to the best shape characteristics of the backing faces of the blades for an opposite direction of propulsion, i. e., astern. To provide strength and rigidity of the blades, it has been customary to shape the backing face portion of a blade in a convex or bulging manner. This so-called "backing" face is efficiently inactive as far as propulsion is concerned. For example, as pointed out above, the effective horse power for backward or astern movement will be materially less than the horse power available for forward movement, due to the lost efficiency of the propeller screw action when the screw is reversed and the backing face portions are employed to produce thrust. Many attempts have been made by those skilled in the art to form the shape of the backing or reinforcing face to increase the efficiency of the backward movement of the boat, but have met with little success.

In view of the above considerations, it has been an object of my present invention to develop a propeller arrangement having the ability of moving a boat ahead or astern with equal facility and greater efficiency than possible heretofore.

Another object has been to devise a boat arrangement that will further improve its maneuverability and over-all efficiency of operation under actual working conditions.

A further object has been to provide an arrangement for increasing the maneuverability of a boat, particularly from the standpoint of its flanking operation.

These and many other objects of my invention will appear to those skilled in the art from the drawings, the claims, and the specification.

In the drawings:

Figure 1 is a somewhat diagrammatic fragmental elevation showing a propulsion arrangement embodying my invention and incorporated in a twin-screw chambered or tunnel type of boat;

Figure 2 is a somewhat diagrammatic reduced bottom plan view of the boat shown in Figure 1;

Figure 3 is an enlarged partial sectional detail of the propeller arrangement employed in the boat of Figure 1;

Figure 4 is a comparative test chart of a single propeller arrangement as constructed and operated prior to my invention, and of a propeller as constructed and operated in accordance with my invention. In this chart, S. H. P. represents propeller shaft horse power. In the curve A, the relation between thrust per shaft horse power to speed of the shaft is plotted for the conventional single propeller as operated to advance a boat ahead and the broken line C is the same propeller operated to move the boat astern. Broken line curve B represents the operation of a dual propeller as constructed in accordance with my invention for both ahead and astern operations. Curve D shows the relation between shaft speed and horse power.

Figure 5 is an elevation similar to that of Figure 1 showing a modified arrangement of my invention as applied to a single screw type of boat;

Figure 6 is a reduced bottom plan view of the boat of Figure 5;

Figure 7 is a diagrammatic chart representing the fluid actuation by the blades of each propeller wheel of a dual propeller arrangement constructed in accordance with my invention. In laying out this diagram, I contemplate the use of a pair of propeller wheels such as shown in Figures 1, 3, and 7 having a spaced-apart relationship on a common actuating tail or propeller

shaft with blades of substantially identical dimensions and of the same hand, with their most efficient propelling surfaces locked face to face inwardly on the shaft, and in a suitable angular relation.

It was found as the result of a tank test that the facing of the most efficient propelling surfaces outwardly did not provide the most effective thrust results, although they were better than heretofore possible with a single propeller arrangement. Thus, in general, corresponding blade surfaces of the two propellers of my invention face in opposite directions; and preferably, the efficient surfaces oppose or face each other. The left-hand portion shows the wheel stream, the direction of movement of the boat, etc., where the shaft is reversed to effect an astern movement of the boat; the right-hand portion shows the relationship when the shaft is moving in its ordinary propelling direction to advance the boat ahead. In this figure, the blades are shown for a complete revolution of the shaft, namely, for an operation between 0° and 360°, both as to astern or backing and as to ahead or propelling operations.

Figure 8 is a partial sectional view in vertical elevation along the lines of Figure 1 showing an adaptation of apparatus of my invention to an existing or conventional boat and shaft arrangement, requiring the provision of a new fairwater;

Figure 9 is a similar view showing a modified adapting arrangement wherein the tail or end of the propeller shaft is provided with a longer taper turn thereon for receiving the longer sleeve coupling of my propeller combination; in this arrangement, an extended sleeve coupling is provided to compensate for the extension of the taper into the propeller hub. This is also true of the arrangement of Figure 10.

Figure 10 shows another adaptation wherein the tail shaft is pushed or extended backwardly and the propeller hub shaped so that its fore portion corresponds to the adjacent cylindrically shaped portions of the tail or propeller shaft;

Figure 11 is a side sectional detail similar to Figure 3, but showing a modified dual propeller arrangement; and

Figures 12 and 13 are transverse sectional views taken on line XII—XII of Figure 11 and illustrating how an angular relationship of the propellers may be changed about the shaft or axis of rotation.

While in previously mentioned views I show a solid or integral hub for the propeller pair, I contemplate, as shown in Figure 11, the attachment of propeller blades to separate hubs; among other things, such an arrangement obviates the necessity for renewing the entire arrangement in the event that one of the blades is damaged.

Although the present invention was developed particularly from the standpoint of river and other boats requiring considerable maneuverability, it is apparent that its application is not limited to this type of boat or craft and that it can be applied to motor boats, sea-going vessels, etc., and to the excitation of fluids generally.

In accordance with the present invention as shown, for example, in Figure 1, I provide a pair of propeller blades 30 and 31 that in the present embodiment of my invention are cast on a common hub portion 32. Assuming that a counter-clockwise rotation of the propeller screw will be employed for forward propulsion and that a

clockwise rotation will be employed for propulsion astern, then the blade relationship of Figure 1 will apply; the clockwise-counter-clockwise rotation relation may be reversed by changing the angularity of the blades. In this relationship, the fore propeller 30 has its relatively efficient propelling surface facing aft and opposite to the direction of movement of the boat. It is thus apparent that the wheel 30 will be active in the forward propulsion of the boat, see the blades indicated 1-4, inclusive, of the fore wheel propeller 30 during the advance of the boat, as shown to the right of Figure 7.

On the other hand, the aft propeller wheel 31 has the convex or curved backing surface portion of its blades facing aft and its more efficient surfaces facing forward of the boat. Thus, the backing or curved surface portions face in the direction of forward movement of the boat and the efficient operating surface portions face in the direction of backward movement of the boat and are effective for backing action when the propeller is being moved clockwise in the specific example chosen for the purpose of this discussion, see the blades represented diagrammatically 1'-4' in the left portion of Figure 7 of the drawings. As will be noted, the active propelling surfaces of the fore propeller 30 are adjacent to the active propulsion surface of the aft propeller 31, see Figure 1.

A general arrangement such as above set forth shows one propeller 30 with its effective operating faces and its backing faces located for forward propulsion of the boat and a second propeller 31 spaced-apart from the first propeller and preferably in axial alignment on the same shaft with its propulsion and backing faces facing in an adjacent and relatively parallel alignment to those of the first-mentioned propeller, or in such a manner that the blades of the second-mentioned or aft propeller 31 will have their faces arranged for highly efficient backing movement.

The question arises as to whether a pair of propellers of the same hand having adjacently-facing propulsion surfaces can be effectively employed with any degree of efficiency in a screw propeller type of boat when they are installed on a common shaft that is actuated by a common prime mover. By actual tests, it has been definitely determined that sound naval and engineering principles are not violated in employing a pair of propellers of the same hand so mounted for common rotation ahead or astern on the same axis. Such tests show that when the dual propellers are suitably arranged, one can be effectively employed for one direction of movement of the boat without setting up prohibitive operating reactions with the other propeller. In the present arrangement, during the forward propulsion, the backing propeller 31, in effect, floats in the wake or slip stream, and vice versa, during the backing operation when the backing propeller is the active one. The distance between propellers is selected upon considerations of the contemplated speed of operation of the propeller shaft as well as from the standpoint of the pitch, area, and number of the blades. The radial angular location of the blades of one propeller with respect to that of the other propeller in a preferred arrangement is substantially the same, and depending upon the desired speed of operation and the distance between the propellers on the shaft, the wheel or slip

streams of the blades of the active propeller wheel will pass through the spacing between adjacent propeller wheels and between the spacing of the blades of the floating propeller with a minimum obstruction to flow. This is due to the relative relationship and angularity of the blades of the propeller wheels, taking into consideration the slip stream and blade velocities.

From the above discussion, it will be apparent that the relative distance or cooperatively advanced relation between propeller wheels may be regulated axially to conform to the speed of rotation and the pitch angle or angles of the blades to provide additional compensation in time and distance, in order that the propeller wake or slip stream issuing from the blades of the active propeller will pass substantially directly by or between the blades of the floating or inactive propeller with a minimum of distortion and interference. The entire arrangement due to its simplicity also eliminates the need for additional appendages or protuberances that normally produce turbulence and eddies.

Such an installation of an additional propeller 25 on the same extension of the tail shaft which takes the usual propeller has been found to involve no interference with or restriction of the space such as would prevent the maintenance of free and unobstructed flow of the water. 30 That is, the propeller arrangement of my invention can be readily applied to existing boat installations as illustrated, for example, in Figures 8-10, inclusive.

Since as indicated on the curves of Figure 4, 35 my arrangement of propellers makes possible the same propulsive effect in ahead and astern movements of the boat and very materially increases the backward efficiency over the normal efficiency of the conventional propeller, it will be apparent that it makes possible a surprising increase in checking, backing, and maneuverability of a boat employing the features thereof. It navigates in extremely high or swift current to much better advantage than any river boat of the conventional propeller type. It is believed that the present invention is the fulfillment of the last need or requirement in the operation of screw propeller type of boat to place such operation on entire parity with a stern-wheel type of boat 45 in all departments, and particularly, from the standpoint of its ability to back with full power as against a fraction of the amount under present installations. The arrangement overcomes the efficiency defects of attempting to employ the backing faces of a propeller for propulsion astern. As intimated above, a convex backing surface is formed primarily from the standpoint of strengthening and reinforcing the efficient propelling face or surface of the blade. The present arrangement also to a marked extent increases the ability of the boat to respond to rudder reactions, due to the impingement or reaction of a wake stream having higher velocity.

Again referring to Figures 1, 2, and 3, I have therein shown a propeller apparatus embodying my invention as applied to a chambered or tunnel type of twin screw tugboat 10 having a drive shaft combination 20 consisting of a primary shaft 22 and a protective tubing 21. The shaft 22 extends through stern bearings 23 of the boat 10 and is journaled within bearings 25 supported by a vertical post or V struts 24 and having a rope guard 26. A conventional rudder arrangement has been shown, and full details

relating to the same may be obtained from a study of my Patent 1,327,643. A steering rudder 12 may be of the partially unbalanced type; 14 designates a flanking propeller that may be of the balanced or unbalanced type. Further details as to the rudder arrangement are omitted in that the present invention does not pertain thereto. In the sectional detail of Figure 3, it will be noted that the two propeller wheels 30 and 31 comprise blades cast on a common hub 32 that is suitably keyed on a tapered end portion 21 of the propeller or tail shaft 22. A fairwater or protective cap 35 is removably secured by cap screws 36 upon end portions of the hub 32. A nut 34 removably locks hub 32 upon the tapered tail shaft end 27.

In the embodiment of my invention shown in Figures 5 and 6, I have illustrated a single engine, single screw boat having a propeller shaft 20 provided with wheels 30-31 that are mounted in the manner shown in Figure 3. In this arrangement, a single rudder 42 is operably positioned in the usual manner between the counter and rearwardly extending portion 43 of stern frame 44 of the boat 40.

In Figure 8, I have shown an apparatus arrangement for adapting my invention to an existing propeller or tail shaft without changing its position or extension. The two propellers 30 and 31 are formed as a single casting on hub 32, the forward portion of the hub corresponding to the ordinary hub of an ordinary propeller to fit over the usual tapered end portion 27a of the propeller shaft, and the adjacent aft portion is recessed to receive a specially formed fairwater 45 having a cylindrical portion 47 that is adapted as a nut to engage a threaded portion 28a of the tail shaft 22a.

In Figure 9, I have shown another arrangement in which the propeller shaft combination 22a is provided with a coupling sleeve 19b that is additional to conventional sleeves 19 in such a manner that the shaft can be separated enough to compensate for the extension thereof necessary for the propeller wheel 31. The end of the shaft 27b is tapered along a length portion corresponding to the length of the hub of the propeller unit. A usual form of fairwater cap arrangement 34 and 35 may be employed. Figure 10 is an arrangement similar to Figure 9 in that the shaft is extended in the same manner but no attempt is made to provide a full tapered engagement with the length of the propeller hub. In other words, the ordinary form of hub arrangement is employed in which the fore portion 27a is tapered and the rear portion 22a is cylindrical. The hub shaft 42c, itself, is tapered a little differently than in the conventional installation in that the fore portion, corresponding to the width of the inner wheel 30, is formed with a cylindrical surface while the aft portion, corresponding to the aft wheel 31, is formed with the usual tapered surface.

Another important feature of the present invention is that the increased velocity of slip stream, made possible by the higher backing efficiency, materially increases the reactive effectiveness of the fluid stream upon the flanking rudder or rudders. This is true since rudder action is directly dependent upon the velocity of water projected upon a rudder surface.

It has been customary to provide ferry boats with fore and aft propeller screw and rudder arrangements, in order that the boats may move ahead and astern with substantially equal facil-

ity; the fore arrangement being clutched out for ahead movement; the aft arrangement being clutched out for astern movement. By employing the dual-propeller arrangement of my invention fore and aft of such a boat, I eliminate the need for clutching or cutting out one arrangement and decrease the propeller horse power requirements by substantially one-half—maneuverability will have a marked increase. Of course, a single dual-propeller arrangement fore or aft of the boat can also be utilized, since as previously pointed out, the thrust or efficiency is the same for ahead and astern boat movement. Other uses and applications of my invention will appear to those skilled in the art of fluid actuation.

Although I have for the purpose of illustration shown my invention as applied to a twin-screw type of propeller boat in Figures 1 and 2, and as applied to a single-screw type of tug in Figures 7 and 8, it will be apparent that it can be readily adapted to other arrangements and that its principles are, in general, applicable to any conventional craft arrangement whether for use on river, lake, or ocean. For example, my twin propeller arrangement can be effectively utilized with a high efficiency in a sleeve or shroud wherein the propellers operate within a substantially enveloping cylindrical arrangement.

Although in an ordinary installation I prefer to select the spacing between the pair of propellers as well as the radial angular relationship of the blades of one propeller with respect to the blades of the other propeller upon the basis of a contemplated operation of the craft or boat in question, and to then cast them in this relation, I also contemplate providing means for adjusting the radial angular relationship of the blades and the distance between blades after the propeller wheels have been formed. As shown in Figures 11 and 12, I provide the propeller wheel 30 with a hub 52 that is separate from a hub 53 of the wheel 31. Space rings or shims 54 are provided between the hubs 53 and 54 to permit adjustment of the spacing between the propeller wheels on their common actuating shaft 22. The radial angular relation of the blades of wheels can be adjusted by removing the longitudinal mounting single key 55 from keyway 56 and turning one of the wheels with respect to the other; the single key 55 can then be replaced by two keys one of which can be distorted as indicated by 55' in Figure 13 to hold the wheels in their adjusted relationship. Figures 12 and 13 show one blade 30 as angularly shifted from position a—a to position b—b; either or both of the propeller wheels may be thus radially-angularly adjusted.

I contemplate tilting or providing an angular rake of the blades or an expanded pitch toward their tips as circumstances may require and as practised in the present state of the art as to conventional single propeller arrangements. It is apparent that each wheel may be provided with a suitable number of blades, although I prefer to provide blade pairs having substantially the same characteristics and dimensions. Propeller arrangements of my invention can also be employed at any suitable location with respect to a craft or boat such as at fore, aft, port, or starboard positions, or any combination of these positions.

In view of the above considerations, it is apparent that many modifications, additions, subtractions, adaptations, and changes can be made

without departing from the spirit and scope of my invention as indicated in the appended claims.

I claim:

1. A propulsion system for a screw propeller type of craft comprising a pair of propeller blades, each of said blades having the same hand, one of said blades being axially spaced from the other propeller blade, each of said blades having a face of substantially planar outline and a back-
ing face of substantially curvilinear outline, the planar face of one of said blades being positioned in an opposed and facing relationship with respect to the planar face of the other blade in such a manner that one planar face will effect forward movement of the craft and the other planar face will effect aft movement thereof.

2. A propulsion system for a screw propeller type of craft comprising a hub portion, a set of propeller blades extending radially in substantially peripheral alignment from a portion of said hub, a second set of propeller blades extending radially outwardly from a portion of said hub in substantially peripheral alignment behind and in axially spaced relationship with respect to the first-mentioned portion thereof, the blades of

each set having one substantially planar face portion and a substantially curvilinear face portion, the planar face portions of the blades of one of said set being operably positioned in an opposed and facing relationship with respect to the planar face portions of the blades of the other set.

3. A propulsion system for a screw propeller type of craft comprising a hub portion, a set of propeller blades extending radially in substantially peripheral alignment from a portion of said hub, a second set of propeller blades extending radially outwardly from a portion of said hub in substantially peripheral alignment behind and in axially spaced relationship with respect to the first-mentioned portion thereof, the blades of each set having one substantially planar face portion and a substantially curvilinear face portion, the planar face portions of the blades of one of said set being operably positioned in an opposed relationship with respect to the planar face portions of the blades of the other series, the blades of one series being positioned in substantial alignment with respect to the blades of the other series with respect to a longitudinal axis of said hub.

THOMAS R. TARN.
